FRONT OF A BANK DEPOSITORY

Henry Dreyfuss, South Pasadena, Calif., assignor to The Mosler Safe Company, Hamilton, Ohio, a corporation of New York

Application November 21, 1955, Serial No. 38,971

Term of patent 14 years

Figure 1 is a perspective view of the front of a bank depository showing my new design.

I claim:

The ornamental design for the front of a bank depository, substantially as shown.
